FIG 2

FIG 4

FIG 3

Harry W. Smith
INVENTOR

BY F. E. Shannon
ATTORNEY

UNITED STATES PATENT OFFICE.

HARRY W. SMITH, OF AKRON, OHIO.

GOLF APPLIANCE AND EXERCISING DEVICE.

Application filed December 17, 1920. Serial No. 431,448.

To all whom it may concern:

Be it known that I, HARRY W. SMITH, a citizen of the United States, residing at Akron, in the county of Summit and State 5 of Ohio, have invented new and useful Improvements in Golf Appliance and Exercising Devices, of which the following is a specification.

This invention relates generally to certain 10 new and useful improvements in exercising devices and has particular relation to a new and novel device which may be employed for the purpose of acquiring proficiency in playing the game of golf.

15 The primary object of the present invention resides in the provision of a golf appliance particularly designed for instruction in the art of striking a golf ball, the same being capable of use either within a 20 home or upon an open field.

A further object of the invention has reference to a golf appliance and exercising device wherein a rubber ball or balloon is elastically anchored to a supporting mat and 25 instantly returns to a set-up position on the mat after being struck by a golf club.

A still further object of the invention includes the specific formation of a rubber ball 30 wherein one side thereof is provided with a flattened surface to permit the ball to remain in a fixed position when so placed.

35 The method of forming the ball also enters into the invention, the same including a circular plate having an open side of a ball or balloon enclosing the same and vulcanized thereto to form an integral structure.

The invention primarily constitutes a golf 40 instructing device that may be employed in the home for perfecting certain drives, especially the driver and brassie shots and also creates sufficient exercise for a person when a golf course is inaccessible.

With the above general objects in view 45 and others that will appear as the nature of the invention is better understood, the same consists in the novel construction, combination and arrangement of parts to be herein- after more fully described and then claimed.

In the accompanying drawing forming a 50 part of this application and to which reference is had by like characters designating corresponding parts throughout the several views:—

Figure 1 is a perspective view of a golf 55 appliance constructed in accordance with the present invention showing a mounting mat

for a rubber bag, ball or balloon elastically maintained upon the upper face thereof.

Figure 2 is a longitudinal sectional view taken on line 2—2 of Figure 1 showing the 60 manner of elastically retaining the golf ball on the mat.

Figure 3 is a perspective view of the mounting mat in inverted position disclosing the longitudinal recess in the bottom 65 face of the mat for the elastic ball-anchoring cord and,

Figure 4 is a cross sectional view of a golf ball or balloon constructed in accordance with this invention.

Broadly defined, the invention comprises a mounting member 1, an object member 5 and an elastic connecting member 7 which is adapted to normally hold the object member in a certain position on the mounting mem- 75 ber.

Briefly described, the present invention aims to provide a device employed in the instruction of golf and also intended as an exercising device. There is provided a 80 mounting mat of any desired configuration, although represented in rectangular form having a longitudinal groove or cut out portion in the bottom face thereof with a depending stud or button extending into said 85 groove adjacent the inner end, while an opening is formed in said mat at the outer end of the groove. A rubber golf ball, bag or balloon is mounted upon the upper face of the mat and carries an elastic cord depend- 90 ing through the mat opening and extending longitudinally of the groove for attachment to the button.

The process of forming the ball or balloon 95 also enters into the gist of this invention, the same including a rubber disk having an annular groove in the periphery thereof into which groove the walls of an opening in a balloon or bag are received and subsequently vulcanized thereto to form an integral homo- 100 geneous structure.

While it is not intended that the mounting mat be limited to any particular design or shape there is illustrated by the reference numeral 1 a mat of rectangular 105 form constructed of rubber or other suitable material with a longitudinal groove or cut out portion 2 formed in the bottom face thereof so as to extend inwardly from adjacent one end of the mat and terminate in 110 proximity of the center thereof. The groove 2 is of sufficient depth to provide a space for

a depending lug or button 3, having the lower end thereof terminating in the same plane as the bottom face of the mat, the button 3 being formed adjacent the inner 5 end 2^a of the slot. For purposes presently to appear an opening 4 extends through the mat 1 adjacent the outer end 2^b of the groove 2 constituting a passage from said groove to the upper face of the mat.

10 A rubber bag or ball 5 has a flat disk portion 6 formed upon one side thereof adapted normally to seat over the mat opening 4 and to retain the ball in this position, an elastic cord 7 is secured as at 7' to the disk 15 portion 6 of the ball, the cord extending through the opening 4 and longitudinally of the groove 2 for anchoring upon the button 3 as clearly shown in Figures 2 and 3.

This invention should not be limited to the 20 exact type of ball employed, one novel method of forming the same being illustrated in Figure 4, there being provided a disk 6^a having a peripheral groove 6^b into which the walls 5^a of the opening in the ball 5^b 25 are received. The connected disk and ball are then treated, as by vulcanization to provide an integral homogeneous structure and providing a ball with a flat side that is capable of being set up contrary to rolling 30 motion. The reference characters 7^a are used to designate one form of the elastic cord 7 which may be inserted within a central opening formed in the disk 6^a and permanently retained therein by vulcanization 35 or otherwise secured thereto.

In the use of the device, the mat 1 is preferably placed upon a flat surface, such as a 40 floor, when used within a house with the groove 2 adjacent the floor and the ball 5 presented for striking with a golf club. The ball 5 may be struck with unlimited force 45 by a golf club without danger of breaking the same and when so struck the ball will be moved to the dotted line position shown in Figure 2 and offer sufficient resistance to the golf club to eliminate all possibility of a wild swing. The direction that the ball will travel in being so struck will indicate to a person the exact point of engagement 50 of the head of the golf club with the ball. With a device of this kind great accuracy may be attained in striking a golf ball, while at the same time it offers convenient, efficient means whereby healthful exercise may 55 be obtained whenever desired. During inclement weather and when golf courses are inaccessible the device may be employed in the home to give sufficient exercise and practice. It is also intended that this appliance 60 may be employed upon an open field or wherever desired as the only area required in the use of the same is for a full swing of a golf club, inasmuch as the ball travels only a few inches in distance from the mat. 65 The ball 5 is also capable of use detached

from the mat 1, affording amusement by using the elastic cord to drive the same against objects to produce unusually loud sounds.

The ball 5 may also be used as a practice 70 ball without the elastic cord 7 and without the mat 1, inasmuch as the ball is of such light weight that it can be used indoors without danger of injury or breakage to other objects and when used out of doors it can 75 be driven but a short distance and is therefore easily and quickly recovered.

While there is herein shown and described the preferred embodiment of the invention, it is to be understood that various changes 80 may be made in all details illustrated without departing from the spirit of the invention as set forth in the subject matter claimed.

Having thus described my invention what I claim as new and desire to secure by Letters-Patent is:—

1. A golf appliance and exercising device comprising a mounting member, a ball normally disposed in a certain position thereon and an elastic connecting member therebetween, said connecting member arranged to permit the ball to be driven therefrom and adapted to automatically return the same to its initial position thereon. 90

2. A golf appliance and exercising device comprising a flexible mat, a ball superposed in a certain position on said mat and an elastic cord connected to said ball and to the underside of said mat for normally retaining the ball thereon, so that it may be propelled from and automatically returned to 100 said position. 95

3. A golf appliance and exercising device comprising a mat, the bottom face of the mat having a longitudinal groove therein, a button depending from the upper wall of said groove, said mat having an opening therein communicating with said groove at a point spaced from said button, a ball supported on said mat over said opening and an elastic cord carried by said ball and extending through the mat opening and groove for attachment to said button. 105 110

4. A golf appliance and exercising device comprising a mat, a button depending from the bottom face of said mat and a ball disposed on the upper face of the mat and having an elastic cord connection with said button, whereby the ball is returned to the mat after being struck by a golf club. 115 120

5. In a device of the class described, the combination with a mat, of a ball and elastic means whereby the ball may be normally retained in a certain spot thereon, said means arranged to permit the ball to be moved a limited distance from said spot and arranged to return the ball when so moved to a teed position on said spot. 125

6. In a device of the class described, the combination with a mat, of a ball having a 130

- flat side and an elastic connection between the flat side of the ball and the mat, said connection adapted to yieldably hold the ball in a certain position on said mat with 5 the flat side thereof contacting therewith.
7. In a device of the class described, the combination with a mat, of a ball elastically retained thereon and including a relatively thick disk portion and a relatively thin 10 spherical portion vulcanized thereto.
8. In a device of the class described, the combination with a mat, of a ball and means to elastically retain the ball thereon said ball including a relatively thick disk portion 15 and a relatively thin spherical portion vulcanized thereto, said retaining means embodying a cord permanently secured to said disk.
9. In a device of the class described, the 20 combination with a mat of a ball having a tee and an elastic cord coaxially secured in the tee portion of said ball, the other end thereof being secured to the underside of said mat so as to normally retain the ball in 25 a teed position at a certain spot thereon.
10. A practice and amusement ball comprising an elastic, hollow, inflated substantially spherical body having a flat relatively thick base and an elastic cord extending 30 axially through said base and secured thereto.
11. A practice and amusement ball comprising a relatively thin, hollow, elastic, inflated body provided with a thick, disk-like 35 base and an elastic cord secured to said base.
12. In a device of the class described, the combination of a base member, an object
- member and means to elastically secure said object member to said base member so that the same will be normally held in a certain 40 position thereon, but may be driven therefrom and when so driven automatically returned to said position.
13. In a device of the class described, the combination of a base member and an object 45 member and means to secure said object member to said base member so that the same is normally held in a certain position and which may be driven therefrom and when so driven will be automatically 50 returned to said position.
14. In a device of the class described, in combination, a mat, a ball, and means to yieldably secure the ball in a certain spot on the upper face of said mat so that the same 55 may be driven from the mat and automatically returned to said spot thereon.
15. In a device of the class described, a mat having an elongated passageway disposed longitudinally thereof on the underside thereof, an opening leading from the forward end of said passageway to the upper 60 face of said mat, a ball, an elastic cord having one end connected to the ball and extending through said passageway with the free 65 end thereof secured at the other end of the passage; said cord adapted to normally hold the ball on the upper face of the mat at a point above said opening and adapted to return the ball to said point when the same 70 is moved therefrom.

In testimony whereof I have hereunto set
my hand.

HARRY W. SMITH.
